GOLFING VEHICLE OR SIMILAR ARTICLE

Glenn R. Thomas, 3010 Military, Oklahoma City, Okla.

Filed Aug. 6, 1959, Ser. No. 57,084

Term of patent 7 years

(Cl. D14—3)

FIG. 1

FIGURE 1 is a three-quarter rear perspective view showing a golfing vehicle or similar article embodying my new design;

FIGURE 2 is a three-quarter front perspective view of the opposite side thereof; and,

I claim:

The ornamental design for a golfing vehicle or similar article, substantially as shown.
